ROCKER ARM FOR INTERNAL-COMBUSTION
ENGINESJohn R. Winter, Jr., Detroit, Mich., assignor to
John R. Winter, Sr., Detroit, Mich.

Application November 21, 1949, Serial No. 128,621

4 Claims. (Cl. 74—519)

1

The present invention relates to improvements in the construction of rocker arms for internal combustion engines of the overhead valve type.

The primary object of the invention is to provide improved means for controlling the feeding of lubricating oil to the valve tappet end of such rocker arms.

It is the usual practice in present-day overhead valve engines to supply lubricating oil under pressure through a longitudinal bore in the rocker arm shaft, communicating radial ports in the shaft being provided inside the hub of each rocker arm to deliver the oil to oil channels in the arm, the channels formed in the arm being designed to conduct metered quantities of oil to opposite ends of the arm. Great difficulty is encountered in the proper metered feeding of oil to the valve ends of such rocker arms because of the fact that if too much oil finds its way to the valve end of an arm and comes into engagement with the valve stem, increased oil consumption is apt to occur, particularly in worn engines, because of the tendency to draw oil into the cylinder along the valve stem, between the stem and its guide, on each suction stroke. In my previously filed application Serial No. 78,217, filed February 24, 1949, I have disclosed an arrangement wherein oil is conducted upwardly through a generally vertical riser hole in the rocker arm, and then allowed to flow to the ends of the arm through open-topped channels, a novel metering clip being provided over the open upper end of the riser hole to prevent upward squirting of oil from such hole, and also to meter the quantity of oil which is allowed to flow into the open-topped channels for conduction to the ends of the arm. With the aid of such metering clips, very accurate control of the quantity of oil delivered to the top channels is provided and decreased oil consumption without sacrifice of satisfactory lubrication can be obtained. The oil metering and control clip disclosed in such prior application is adapted for use with several previously known types of rocker arms having groove-like oil channels extending along their tops. Insofar as I am aware, all such top oil channels heretofore employed have been of uniform cross section throughout their length. I have found that with such previously known types of rocker arms, although the installation of the clip device greatly improves the accuracy of oil control and reduces oil consumption for the reasons indicated, a new limiting factor, preventing the attainment of the utmost efficiency appears, even with the aid of such clips, at high engine speeds. With such

2

clips, the oil flow to the valve end of the arm can be reduced to the absolute minimum which will assure satisfactory lubrication, but at high engine speeds, there is a tendency of the oil to "build up" or "pile up" on top of the arm, and flow over the side of the arm, rather than flowing smoothly and continuously along the oil channel to the outer end of the arm.

It is also an object of the present invention, therefore, to overcome the difficulty just outlined, and to provide a simple, inexpensive, and reliable rocker arm construction adapted for use with an oil metering and control clip of the indicated variety, the arrangement being such that the clip may be designed to reduce the oil flow to the valve end of the arm to the absolute minimum required for satisfactory lubrication, the arm itself being so designed that, even at high speeds, oil will not flow from the top oil channel over the side of the arm. The invention attains this objective by graduated contouring of the top oil channel which leads to the valve end of the arm, the cross-sectional area of such channel being increased progressively toward the valve end of the arm.

Other objects and advantages of the invention will become apparent upon consideration of the present disclosure in its entirety.

In the drawing:

Fig. 1 is a side elevational view of a rocker arm incorporating the principles of the present invention;

Fig. 2 is a top plan view thereof;

Fig. 3 is a central vertical sectional view taken substantially on the line 3—3 of Fig. 2 and looking in the direction of the arrows; and

Figs. 4, 5 and 6 are cross-sectional views taken substantially on the lines 4—4, 5—5 and 6—6, respectively, of Fig. 1, and looking in the direction of the arrows.

The general construction and arrangement of the principal parts of the rocker arm may correspond to those of the rocker arms disclosed in my previously filed copending applications Serial Nos. 701,150 now patented and 78,217. The body of the arm is blanked and formed from a single piece of sheet metal, shaped and folded to provide two laminæ 15, 16 which lie against one another. The laminæ are secured together by an integral part 10 at the push pin end, such part 10 being wrapped around the stem 12 of the push pin element. The laminæ 15 and 16 are also secured together by welding, as at the points designated 17, 18 and 19. Aligned hub-receiving openings as 20 are formed in intermediate wid-

ened portions of the laminae, and such openings are aligned when the laminae are folded together. A tubular sheet metal hub 22 is projected through the hub opening thus formed and the hub is bulged as indicated at 24 and 25 on opposite sides of the arm laminae to secure the hub and arm portions together and additionally hold the laminae against separation. A bearing sleeve 26 is fitted in the hub 22.

In the formation of the bulged portions 24, 25, the metal which is bent outwardly from the surface of the hub to define each bulge is curved about a small radius in such manner as to leave annular internal, generally V-shaped grooves 28, 30. The inner faces of the grooves 28, 30 are closed by the bearing sleeve 26 so that the grooves form annular internal channels extending interiorly of the hub assembly and completely there-around.

The bearing sleeve 26 is provided on its inner face with an internal groove 32 and communicating radial holes 33, 34 adapted to communicate with a radial oil feed port (not shown) in the rocker arm shaft. In registry with one of the holes as 33, a slot 35 is formed in the hub 22 extending in an axial direction entirely through the hub wall and long enough to provide communication between the hole 33 and the internal channel 30 in the hub. A similar axial slot 36 is formed in the hub in registry with the aperture 34 in the bearing sleeve and of such length as to provide communication between aperture 34 and internal oil channel 28. A longer axial slot 38 is formed in the hub 22 in registry with the oil riser passage 40 and connecting such passage with both of the channels 28, 30. Oil supplied to the holes 33, 34 from the shaft, therefore, must travel through the slots 35, 36 to the internal channels 30, 28, respectively, and then around the channels 30 and 28 to passage 38 before such oil can pass upwardly through the riser passage 40 to the top of the arm.

Oil discharged through the riser is conducted lengthwise over channels formed in the top surface of the arm to the end bearing pads, but the amount of oil which can reach such top passages is restricted by special metering means including the damming and metering ears 48 and 50 and the oil control and metering clip, generally designated 42. Clip 42 is fitted over the arm in such manner that a top baffling portion 44 thereof is located spacedly above the open top of the riser passage 40, to intercept any oil which tends to squirt from such passage, and divergent, downwardly inclined, deflecting guide portions 45 of the clip are adapted to guide excess oil angularly downwardly and away from the top of the arm. A metered quantity of oil finds its way longitudinally of the arm through a pair of V-shaped channels as 46 defined by the somewhat divergent upstanding ears 48, 50. The ears are integrally formed and angularly bent from the material of the laminae of the arm sections. An area between the two pairs of upstanding ears is formed as a notch-like depression 52 in the top of the arm and defines a predetermined laterally open space above the riser passage 40 and beneath the baffle portion 44, such space being open at the sides beneath the deflecting guides 45 to allow excess oil to escape at the sides.

Due to the relatively high surface tension and viscosity of the oil, the space 52 tends to remain substantially full of oil, and a part of such oil finds its way longitudinally between the ears 48, 50 and travels along the top edges of the laminae 75

to the ends of the arm. As explained in my previously filed applications referred to, substantially V-shaped channels of shallow form may be provided along the top edge of the arm simply by folding the blank in the proper direction. This forms a natural V due to the fact that some drawing of the metal occurs during the shearing thereof in the blanking operation, so that one edge of each lamina of the folded blank will be somewhat higher than the other, the higher edge being placed at the outside by the act of folding the two sections about their end portion 10. In the absence of special treatment, this would provide a shallow channel of substantially uniform cross section extending outwardly to the ends of the arm. In the present construction, such channels are of nonuniform cross section, however, as will appear.

The ends of the clip 42 are bent downwardly 20 to provide terminal edges 54, 55 which lie closely adjacent the tops of the arm and coat with the ears 48, 50 and with the channels in the top of the arm to limit in a positive manner the volume of oil which can pass between such ears and out 25 from under the ends of the clip into the top channels. If the spacing between the ears and the proportions of the clip structure 42 are properly engineered, it will be appreciated that the amount of oil allowed to pass outwardly under 30 the clip edge 54 toward the valve end of the arm can be accurately metered and held at a proper value.

Where the top channel leading toward the valve end is of uniform cross section, as in the arms 35 of the prior art, the operation is entirely satisfactory at low engine speeds, and a very substantial improvement is obtained at all engine speeds, including high speeds, but I have found that at 40 high engine speeds the reciprocation of the arm is so rapid that the smooth flow of oil along the top channel to the valve end is interfered with. At high speeds the oil tends to "pile up" in the channel, and a substantial quantity of it will flow out of the top channel leading to the valve end 45 and over the sides of the arm approximately in the region designated 58. Some of such oil will run outwardly along the sides of the arm toward the head of the push pin.

In accordance with the present invention, I 50 provide a top oil channel 60 which is of gradually increased width and depth as it extends outwardly from the ears 50 to the valve end of the arm. Such tapered slot may be formed by contouring the edges of the laminae before folding them together, and although such groove is 55 shown as of straight-sided V cross section and uniformly tapered form, it will be appreciated that this specific contouring is subject to variation. The increased depth and width of the slot 60 toward the outer end compensates for the resistance of the oil to proper outward flow which develops at high speeds and retains the oil in the channel without permitting it to flow over the side, so that it may be fed in the intended manner downwardly through the passage 62 to the 65 pad surface of the head portion 14 of the valve bearing element or push pin 12, where it may perform its lubricating operation without escaping over the side of the arm.

Due to the tendency of the graduated oil channel 70 to retain the oil against such escape over the sides of the arm at high speeds, it is possible to reduce the spacing between the metering ears 50 to the minimum, so that no excess oil, not actually needed for lubricating the push pin bearing

need be supplied to the top channel 60. Over-lubrication at the valve end is thereby effectively prevented, with a consequent important saving of engine oil consumption and resultant increase of engine efficiency.

It will be understood that although the disclosed metering means for preventing delivery of an excess volume of oil to the top channel 60 comprises the clip structure 42 and the coacting damming ears 50, different metering means could be employed without detracting from the value of the graduated top channel 60, which will perform its operation regardless of variations of the metering means. For example, a different type of metering means is disclosed in Patent No. 2,288,831, which is intended to allow a relatively large and controlled quantity of oil to escape over the sides of the arm close to the riser hole. The specific metering means disclosed herein, however, is my preferred mode of attaining the metering action in conjunction with the graduated feeding channel means 60.

While it will be apparent that the preferred embodiment of the invention herein disclosed is well calculated to fulfill the objects above stated, it will be appreciated that the invention is susceptible to modification, variation and change without departing from the proper scope or fair meaning of the subjoined claims.

What is claimed is:

1. A rocker arm construction for internal combustion engines, including a hub portion and an arm, and a bearing element carried by the outer end of said arm, an oil riser passage-defining portion extending upwardly from the hub portion to the top of the arm, portions of said arm defining an open-topped channel extending longitudinally along the upper edge of the arm to provide communication between said riser passage and said bearing element, said channel having outwardly diverging wall portions imparting to said channel a graduatedly increased cross-sectional area toward said outer end of the arm which carries said bearing element, and combined metering and baffling portions having a baffling part extending over but spaced above the upper end of the riser passage and a metering part restricting the delivery of oil from the riser passage to the channel.

2. A rocker arm construction for internal combustion engines, including a hub portion and an arm, and a bearing element carried by the outer end of said arm, an oil riser passage-defining portion extending upwardly from the hub portion to the top of the arm, portions of said

arm defining an open-topped channel extending longitudinally along the upper edge of the arm to provide communication between said riser passage and said bearing element, said channel-defining portions being formed of substantially flat and straight walls arranged in V-form and which diverge from one another to graduatedly increase the cross-sectional area of the channel toward said outer end of the arm which carries said bearing element.

3. A rocker arm construction for internal combustion engines, including a hub portion and an arm, and a bearing element carried by the outer end of said arm, an oil riser passage-defining portion extending upwardly from the hub portion to the top of the arm, portions of said arm defining an open-topped channel extending longitudinally along the upper edge of the arm to provide communication between said riser passage and said bearing element, said channel having outwardly diverging wall portions imparting to said channel a graduatedly increased cross-sectional area toward said outer end of the arm which carries said bearing element.

4. A rocker arm construction for internal combustion engines, including a hub portion and an arm, and a bearing element carried by the outer end of said arm, an oil riser passage-defining portion extending upwardly from the hub portion to the top of the arm, portions of said arm defining an open-topped channel extending longitudinally along the upper edge of the arm to provide communication between said riser passage and said bearing element, said channel having outwardly diverging wall portions imparting to said channel a graduatedly increased cross-sectional area toward said outer end of the arm which carries said bearing element, and metering means restricting the rate of oil delivery from the riser passage to the channel.
